UNITED STATES PATENT OFFICE.

JAMES MACPHAIL, OF BLUE ISLAND, ILLINOIS, ASSIGNOR TO THE PLANO MANUFACTURING COMPANY, OF CHICAGO, ILLINOIS.

DESIGN FOR A BELT-BUCKLER.

SPECIFICATION forming part of Design No. 30,488, dated April 4, 1899.

Application filed March 11, 1899. Serial No. 708,764. Term of patent 14 years.

To all whom it may concern:

Be it known that I, JAMES MACPHAIL, a citizen of the United States, residing at Blue Island, in the county of Cook and State of Illinois, have invented and produced a new and useful Design for Belt-Bucklers, of which the following is a specification.

handle portion A, provided with two separate arms B and C. The arm B has a curved or hook-shaped end b. The arm C is provided at its extreme point with a small hook c and is also provided with a compound curve.

I claim—

The design for a belt-buckler substantially as herein shown and described.

JAMES MACPHAIL.

Witnesses:

SAMUEL E. HIBBEN,
LOUISE E. SERAGE.

10 Figure 1 is an edge view thereof, and Fig.
2 a side elevation thereof.

The belt-buckler, as shown, consists of a
